ALARM CONTROLLER HOUSING

Marilyn Calderoni, Springfield, and Edward P. Cheslock,
Kennett Square, Pa., assignors, by mesne assignments,
to Gulf & Western Systems Company, New York, N.Y.,
a corporation of Delaware

Filed July 17, 1969, Ser. No. 18,245

Term of patent 14 years

Int. Cl. D29—99; D13—03
U.S. Cl. D72—1

FIG. 1

FIG. 2

FIG. 3

FIG. 6

FIG. 4

FIG. 5

FIG. 1 is a perspective view of an alarm controller housing showing our design;

FIG. 2 is a top plan view thereof on an enlarged scale.

FIG. 3 is a front elevational view thereof on an enlarged scale.

FIG. 4 is a side elevational view thereof on an enlarged scale.

FIG. 5 is a bottom plan view thereof on an enlarged scale.

FIG. 6 is a back elevational view thereof.

We claim:

The ornamental design for an alarm controller housing, substantially as shown and described.
